UNITED STATES PATENT OFFICE.

FRANK REEVES, OF PHILADELPHIA, PENNSYLVANIA, ASSIGNOR TO GARDNER TEXTILE CO., OF NEW YORK, N. Y., A CORPORATION OF NEW YORK.

DESIGN FOR A WOVEN FABRIC.

Application filed May 29, 1923. Serial No. 6,314. Term of patent 3½ years.

To all whom it may concern:

Be it known that I, FRANK REEVES, a citizen of the United States, and a resident of Philadelphia, in the county of Philadelphia and State of Pennsylvania, have invented a new, original, and ornamental Design for a Woven Fabric, of which the following is a specification, reference being had to the accompanying drawing, forming a part thereof.

The drawing shows a piece of fabric embodying my new design.

What I claim and desire to secure by Letters Patent is:

The ornamental design for a woven fabric, substantially as shown.

FRANK REEVES.
